US00D941279S

(12) **United States Design Patent** (10) **Patent No.:** **US D941,279 S**
(45) **Date of Patent:** **** Jan. 18, 2022**

(54) **RFID INLAY**

(71) Applicant: **AVERY DENNISON RETAIL INFORMATION SERVICES, LLC**,
Mentor, OH (US)

(72) Inventor: **Muhammad Rizwan**, Chelmsford (GB)

(73) Assignee: **Avery Dennison Retail Information Services LLC**, Mentor, OH (US)

(**) Term: **15 Years**

(21) Appl. No.: **29/725,427**

(22) Filed: **Feb. 25, 2020**

(51) LOC (13) Cl. **14-03**

(52) U.S. Cl.

USPC **D14/230**
